UNITED STATES PATENT OFFICE.

MORRIS STRICKLER, OF JERSEY CITY, NEW JERSEY.

HAT-PIN.

1,221,624.

Specification of Letters Patent.

Patented Apr. 3, 1917.

Application filed July 6, 1916. Serial No. 107,739.

To all whom it may concern:

Be it known that I, MORRIS STRICKLER, a citizen of the United States, and a resident of Jersey City, in the county of Hudson and State of New Jersey, have invented 5 a new and Improved Hat-Pin, of which the following is a full, clear, and exact description.

This invention relates to hat pins and 10 particularly to an improved arrangement which is designed to be manipulated after the hat has been placed in position, and has for an object the construction and arrangement of parts whereby when the parts are 15 manipulated the hat is positively secured to the head.

Another object in view is to provide a 20 hat pin with movable parts forming interlocking members which when interlocked grasp a quantity of the hair of a person using the device and thereby retain the hat against accidental removal.

In the accompanying drawing:

Figure 1 is a horizontal sectional view 25 through part of a hat disclosing an embodiment of the invention, part of the structure being shown in section.

Fig. 2 is a front view of a pin embodying 30 the invention.

Fig. 3 is a view of the pin shown in Fig. 2 looking at the same from the opposite direction.

Fig. 4 is an enlarged detail perspective 35 view of an operating rod embodying certain features of the invention.

Fig. 5 is a combined clamping plate and cam member.

Referring to the accompanying drawing by numerals, 1 indicates a hat which may 40 be of any desired construction and through the crown of which is forced the rod 2. As shown in Fig. 4 the rod 2 is preferably pointed at 3 and bifurcated at 4 whereby the rod may be thrust through the crown 45 of the hat easily and the bifurcated end receive the ends of arms 5 and 6. A retaining pin 7 passes through these arms at the point where they overlap, said pin also accommodating the coils of a spring 8, which spring 50 engages arms 5 and 6 for giving said arms a continual tendency to move apart or to the position shown in Fig. 1.

The rod 2 is threaded so as to receive the

nut 9, which nut is provided with an ornamental head in order to give a pleasing appearance, said head being, if desired, in the shape of the conventional head now used on hat pins. When the nut 9 is rotated the threaded rod 2 will be moved outwardly and the arms 5 and 6 will be brought into engagement with the cams 10 and 11, whereupon said arms will be swung outwardly or away from the crown of the hat and thereby cause the prongs 12 and 13 to enter the hair 14 (Fig. 1). It will be understood 65 that though the arms 5 and 6 and prongs 12 and 13 are shown flat they may be formed round or any shape without departing from the spirit of the invention.

After the prongs 12 and 13 have passed 70 each other or have become interlocked the hat is then securely fastened on the head, and in order to remove the same it will be necessary to unscrew the nut 9 whereupon the spring 8 will cause the arms 5 and 6 to 75 move back to their former position, as for instance, the position shown in Fig. 1. It will be observed that the rod 2 is flattened and extends through a suitably shaped slot 15 in the plate 16 and the base 17 of cams 80 10 and 11, whereby the rod cannot rotate during the rotation of the nut.

What I claim is:

1. In a hat pin of the character described, a pair of bars pivotally connected together, 85 each of said bars having hair engaging prongs, means for moving said prongs to an open position, a sliding rod connected to said bars at the point of the pivotal mounting of said bars, a pair of stationary abutments limiting the movement of said bars, and a nut acting on said sliding rod 90 for moving the same in such a direction that the rod will move said bars against said abutments and thereby swing the bars from 95 an open position to a closed position.

2. In a hat pin of the character described, a pair of bars pivotally connected together, each of said bars having a prong, a threaded rod connected with said bars by the 100 same pivotal member used in connecting the bars, a spring acting on said bars for normally holding the same in an open position, an apertured clamping plate through which said rod extends, a nut fitting on to said rod 105 and acting on a hat for clamping the hat

against said clamping plate, and a stationary abutment on each side of said rod connected with said clamping plate, said abutments being spaced apart so that when 5 said nut is turned in one direction the rod will pass through the clamping plate and draw the connected ends of said bars into a

position between said abutments and thereby swing the prongs toward each other.

MORRIS STRICKLER.
